UNITED STATES PATENT OFFICE.

AUGUST DEININGER, OF BERLIN, GERMANY, ASSIGNOR TO THE FIRM OF
H. M. D. DEININGER, OF SAME PLACE.

MALTING APPARATUS.

SPECIFICATION forming part of Letters Patent No. 469,851, dated March 1, 1892.

Application filed May 26, 1891. Serial No. 394,142. (No model.)

To all whom it may concern:

Be it known that I, AUGUST DEININGER, a citizen of the German Empire, residing at Berlin, in the Kingdom of Prussia, German Empire, have invented certain new and useful Improvements in Malting Apparatus, of which the following is a specification.

This invention relates to a pneumatic malting apparatus by which the different successive operations to which the barley is subjected in the malting process—such as the removing of the light floating grains of barley, the washing of the barley, the moistening and sprouting of the barley, the heating of the germinated grains, and, finally, the preliminary drying of the malt—can be successively and reliably carried out, so that the manual labor and the expensive plant heretofore required can be dispensed with and that a superior and uniform malt is obtained.

The invention consists of a pneumatic malting apparatus that comprises a germinating-drum having a fixed and a detachable head, a stationary tubular axle having a perforated and a non-perforated portion, an interior removable pipe system formed of an exterior tubular axle and radial perforated pipes, and a partition attached to the end of the exterior axle and having an imperforate center portion and a circumferential flange fitting into the open end of the drum.

The invention consists, further, of the germinating-drum, a tubular stationary axle around which the drum is rotated, an exterior tubular axle having radial perforated pipes, a perforated partition having an imperforate portion, a four-way valve, an air-moistening chamber, an air-heating chamber, and an air-drying chamber connected by valved tubes with said four-way valve, a force-fan connected with the four-way valve and with the stationary tubular axle, and a suction-fan connected with the outgoing end of the drum, as will be fully described hereinafter, and finally pointed out in the claims.

In the accompanying drawings, Figure 1 represents a side elevation, partly in vertical longitudinal section, of my improved pneumatic malting apparatus. Fig. 2 is a vertical longitudinal section of the germinating-drum, drawn on a larger scale. Fig. 3 is a

vertical transverse section of the same. Fig. 4 is a vertical longitudinal section of the germinating-drum, showing the parts composing the same in the act of being separated from each other; and Fig. 5 is an end view of the perforated partition of the detachable pipe system of the germinating-drum.

Similar letters of reference indicate corresponding parts.

Referring to the drawings, A represents the germinating-drum, B the air-moistening chamber, C the air-heating chamber, and D the air-drying chamber, of my pneumatic malting apparatus, which parts are arranged sidewise of each other and placed in communication with each other by a four-way valve E, which will be fully described hereinafter. The ingoing end of the germinating-drum A is connected by an elbow-tube e and tube Q with a ventilating-fan F, which is connected by a pipe P with the four-way valve E, while the outgoing end of the drum A is connected by an elbow e' and tube Q with a suction-fan F', that communicates with the atmosphere. The pressure in the connecting-pipes Q Q' is indicated by pressure-gages H H', which are arranged at the upper part of the same near the ventilating-fans F F', where, also, thermometers I I' are arranged, so as to read off the temperature in said connecting-tubes.

The germinating-drum A is composed of an exterior cylindrical shell, which is provided with a number of glass-covered peep-openings d d, a supply-opening R, and small openings d' d'', which latter are closed by means of plugs d'', and which serve for discharging the moisture of the drum. The drum A is closed at one end by a fixed head A' and at the other end by a detachable head A² and rotated on a fixed tubular axle G', which is extended through the left-hand head of the drum and rigidly connected by a stuffing-box with the connecting-elbow e, and which is closed at the opposite end by a perforated partition M, having a circumferential flange m, by which the partition M is tightly fitted into the end of the drum A. Into the drum A is inserted the detachable pipe system K, which is composed of the tubular perforated axle G and a number of smaller radial pipes a a', which extend in alternating rows or groups from the axle G

and are closed at their outer ends. The tubular axle G is made of slightly-larger diameter than the axle G', so as to be moved readily over the latter until the end of the axle G' 5 abuts against the central imperforate portion of the partition M and is closed by the same, as shown in Fig. 2. The right-hand end of the germinating-drum A is then closed by the solid head A² of the same, between which and 10 the perforated partition M a cylindrical chamber O is formed, the width of which is equal to the width of the circumferential flange m. The imperforate center portion of the perforated partition M is somewhat larger in diameter 15 than the axle G and provided at its center with a fixed eye m', by means of which the entire pipe system K, with its axle G', can be removed from the drum after the right-hand head of the drum is removed, as shown 20 in Fig. 4. The partition M is fitted tightly to the inner circumference of the drum A, but in such a manner that it can be readily removed with the pipes a a', so as to permit the thorough cleaning and repairing of the 25 radial perforated pipes, as well as of the drum A and the axles G and G' of the same. After the cleaning of the parts the pipe system K is returned into position in the drum A by sliding the tubular axle G over the fixed axle 30 G' until its end abuts against the middle imperforate portion of the partition M and the circumferential flange m fits tightly to the right-hand end of the drum, after which the head A² is replaced into position. The tubular axle G' of the drum A is formed of an upper non-perforated portion and of a lower portion, which is provided with openings s. The drum A, with its pipe system K and partition M, is slowly rotated around the stationary axle G' by means of rollers, gear-wheels, or other motion-transmitting mechanisms, 35 which act on the circumferential or toothed rims of the drum. Rotary motion is imparted to the rollers or gear-wheels in the same direction by a suitable transmission, which is composed of belts and pulley transmission, intermediate bevel-gears, and worm-gears, as shown in Figs. 1 and 3.

Any suitable mechanism by which a slow 40 rotary motion is imparted to the germinating-drum around the fixed tubular axle G' can be employed, as I do not desire to confine myself to the special construction shown.

The radial pipes a a' are so grouped around 45 the tubular axle G that one group a alternates with the next group a', as shown clearly in Fig. 3, the tubular axle G being perforated at those points only where the radiating pipes are inserted into the same. The interior axle 50 G' is, however, only partly perforated, its openings s registering with the inner ends of the radial pipes a a', while the imperforate portion of the axle G' serves to close off the remaining portions of the radial pipes a a', 55 so that thereby the currents of air or water introduced into the germinating-drum are ejected only through the pipes at one side of

the inner axle G'. The distance of the groups of radiating pipes a a' from each other is such that the currents of air or water that are forced 70 through the same meet in the space between the tubes. The inner ends of the radiating-pipes a a' are attached into the openings of the tubular axle G, while the outer ends of the same, which terminate near the shell of 75 the drum, are closed. For bracing the outer ends of the pipes a and a' they are connected by means of wires, which are again connected to the ends of the tubular axle G, as shown clearly in Figs. 2 and 4.

The peep-holes d of the drum A serve for observing the progress of the germinating process, while the plugged openings d' d' serve for conducting off the water supplied to the interior of the drum. The larger opening R serves for the charging and discharging of the drum, as well as for removing the light floating barley from the same. It is closed by means of a cover N, which is firmly bolted to the drum.

For permitting the reversing of the germinating-drum A the driving-shaft is provided with a fast and a loose pulley n and n', (shown in Figs. 1 and 3,) by means of which and a suitable reversing-gear the drum can be 95 readily rotated in one or the opposite direction. During the rotary motion thus imparted to the drum the supply of air is so regulated to the drum that it passes through the openings s of the fixed axle G' into the perforated pipes a a' which are then in register with said openings while those pipes a a' which are then located over the non-perforated portion of the axle G' are shut off from the supply of air. As the non-perforated 100 portion is arranged at an inclined angle to the vertical axis that corresponds to the line LL', which the body of barley assumed while being turned in the drum, no air is supplied to those pipes a a' which are at that time outside of the body of barley in the drum.

The four-way valve E is provided with suitable slides and connected, respectively, by tubes B', C', and D' with the air-moistening apparatus B, the air-heating apparatus C, and air-drying apparatus D. The air-moistening apparatus B is composed of a rectangular chamber, in the lower part of which a water-supply pipe f, provided with a number of jet-nozzles, is arranged. The air is drawn in 110 through the opening h and moistened by passing through the spray of water produced by the jet-nozzles. The connection between the chamber D and the valve E is regulated by the slide b', by which, also, the connection can 115 be entirely interrupted. A short pipe h' in the side wall of the chamber B serves for connecting the same with a cooling apparatus, in which the air is cooled by a suitable supply of ice, so that the proper germinating temperature of the air is obtained even when the temperature of the outer air is considerably 120 higher, so that malting can be carried on in the summer season.

The air-heating apparatus C consists of a heating-chamber in which the air to be heated is introduced through a tube C² and conducted over a steam-coil C³, it being drawn through the tube C' and its slide C⁴ to the valve E and through the fan F into the drum A.

The air-drying apparatus D consists of a cylinder having a filling-opening x and a discharge-opening x² for the drying material.

10 The same is provided at the lower part with a perforated false bottom x', the space above the false bottom being filled with a suitable drying material, such as pumice - stone, sponge, calcium chloride, or other suitable material. The air is conducted from the air-drying apparatus D through the pipe D' to the valve E, while an additional connection is made with the lower part of the air-heater C by a tube x³, provided with a slide x⁴, so 20 that the air cannot only be taken through the tube D', but also through the heating apparatus C and its connecting-pipe C'.

By the four-way valve E the drum A can be supplied, according to the relative positions 25 of the slides in the pipes B', C', and D', with the moist, heated, or cooled air, as required by the different stages of the germinating process. The slide T at the upper part of the valve E is kept in reserve for making additional connections, if required. All the air is conducted in sheet-metal tubes of the same diameter, which, like the germinating-drum and its perforated tubes, are protected by a zinc coating.

30 The operation of the apparatus is as follows: The drum A is charged with barley to about one-third of its capacity through the opening R and the space above the barley filled up to a certain height with water, the light barley 35 which floats on the surface of the water being removed through the opening R. For the purpose of thoroughly washing the barley the opening R is closed by the gate N and the drum rotated by the transmitting mechanism 40 by applying the driving-belt to the pulley n. The wash-water is renewed from time to time until all the dirt and impurities adhering to the barley are removed. When the washing is completed, the openings d' d' are 45 closed by the plugs d² and the drum repeatedly supplied with fresh water until the barley is sufficiently softened for the germinating process. The plugs are then removed from the openings d' d' and the drum rotated until all 50 the moisture is removed from the same. The motion of the drum is then interrupted and the swelled barley is permitted to rest, so that it commences to "sweat" and sprout. At this point the jet-nozzles f in the air-moistening 55 apparatus B are set into action and moistened air is drawn by means of the suction-fan F from the chamber B to the drum A, which is rotated again, so that the moistened air is forced by the fan F through the tubular axle 60 G' into the perforated radial tubes a a' in such a manner that all the parts of the swelled

and sprouted barley are penetrated by the moistened air. The entrance of the air into the drum can only take place through the perforations s of the axle G' and the radial 70 pipes communicating therewith, while the non-perforated portion of the interior axle G' prevents the passage of the moistened air into the radial pipes a a', located at that time above said non-perforated portion G². Consequently the moistened air is always supplied to the sprouting barley, which is located at the lower side of the inclined dotted line L L', (shown in Fig. 3,) while no air passes into the space above said inclined line. The moistened air is consequently continuously forced through the sprouting barley by the fan F until it passes, finally, through the perforated partition M into the chamber O and is drawn off from the latter through the pipe Q' by the 80 fan F'. The swelling and sprouting of the barley takes place at a temperature up to 15° Celsius and at a degree of moisture corresponding to this temperature. At this temperature and by the presence of moisture 90 the overheating of the body of barley and the killing of the sprouts are prevented. The germinating takes place uniformly throughout the entire body of barley, the progress of the germinating process being readily observed at any time by the thermometers I and I', the pressure-gages H H', and the glass-covered openings d, so that even the slightest change in the temperature or moisture required by the body of barley can be readily 95 controlled by means of the slides of the four-way valve E. The most dangerous point of the malting process—namely, that of the overheating of the barley—can thus be readily passed by. By the slow rotation of the 100 drum the body of barley in the same is supplied with moist and dry air of proper temperature by means of the radial perforated tubes, the barley kept loose all the time, the sprouting accelerated, and the self-heating of the 105 body of malt prevented, and, as the drum can be readily kept clean, any formation of fungi in the sprouted barley is prevented. When the germinating of the barley is completed, the continued growing of the sprouts has to be 110 immediately interrupted. For this purpose all the slides of the valve E are closed, except that of the tube D', so that cold air is forced from the chamber D into the drum until the sprouts wither. The slide of the tube D is then 115 closed and the slides x⁴ and C⁴ are opened, so that dry hot air is forced by the fan F through the body of barley, by which the preliminary 120 drying of the malt takes place. As soon as the preliminary drying is completed all the 125 slides are closed, the drum emptied, the pipe system K removed from the exterior cylinder or shell, as shown in Fig. 3, all the parts carefully cleaned, then replaced in position, and the drum charged with a new quantity of barley, as before, and operated in the same manner, and so on.

Having thus described my invention, I claim as new and desire to secure by Letters Patent—

1. In a pneumatic malting apparatus, the combination of a stationary tubular axle provided with a perforated portion and a non-perforated portion, a drum rotating around said axle and provided with a stationary head at one end and a detachable head at the opposite end, an exterior tubular axle having a system of radial perforated pipes, said axle being fitted over the stationary axle, a perforated partition attached to the end of the exterior axle and provided with a central imperforate portion, and a circumferential flange fitted into the end of the drum, substantially as set forth.
2. In a pneumatic malting apparatus, the combination of a stationary tubular axle provided with a perforated portion and a non-perforated portion, a drum on said tubular axle, an exterior tubular axle fitted over the stationary axle and provided with radial perforated pipes, and means for rotating the drum around the stationary axle, so that moistened dry cold air or heated air can be forced through the perforated tubes that communicate with the perforated portion of the interior axle, but prevented from passing into the

perforated tubes that are located over the 30 non-perforated portion of the interior axle, substantially as set forth.

3. The combination of a stationary tubular axle having a perforated portion and a non-perforated portion, a germinating-drum on 35 the stationary axle, means for rotating said drum, an exterior tubular axle provided with radial perforated pipes, a perforated partition at the outgoing end of the exterior axle, said partition being attached to said axle and the drum and forming a chamber with the head of the latter, an air-moistening chamber, an air-heating chamber, an air-drying chamber located near the ingoing end of the stationary axle, a four-way valve, tubes having slides for 45 establishing communication between the four-way valve and said chambers, a force-fan connected with the four-way valve and with the ingoing end of the stationary axle, and a suction-fan connected with the outgoing end of 50 the drum, substantially as set forth.

In testimony that I claim the foregoing as my invention I have signed my name in presence of two subscribing witnesses.

AUGUST DEININGER.
